LIVE WELL VALVE

William G. Roller, Purdy, Mo., assignor to
G & R Industries, Purdy, Mo.

Filed Aug. 19, 1974, Ser. No. 498,433

Term of patent 14 years

Int. Cl. D23—01

U.S. Cl. D23—19

FIG. 1 is a side elevational view of a live well valve showing my new design;

FIG. 2 is a second side elevational view taken ninety degrees from that shown in FIG. 1;

FIG. 3 is an elevational view taken from the side opposite that shown in FIG. 2;

FIG. 4 is an elevational view taken from the side opposite that shown in FIG. 1;

FIG. 5 is an elevational view taken from one end thereof; and

FIG. 6 is an elevational view taken from the end opposite that shown in FIG. 5.

I claim:

The ornamental design for live well valve, substantially as shown and described.
